UNITED STATES PATENT OFFICE.

JOHN HENRY THEBERATH, OF NEWARK, NEW JERSEY.

DESIGN FOR A SCARF-PIN.

SPECIFICATION forming part of Design No. 23,514, dated July 31, 1894.

Application filed July 9, 1894. Serial No. 517,013. Term of patent 3½ years.

To all whom it may concern:

Be it known that I, JOHN HENRY THEBERATH, of Newark, in the county of Essex and State of New Jersey, have invented and produced a new and original Design for a Pin, of which the following is a specification.

Reference is to be had to the accompanying drawing, forming a part of this specification, in which the figure shows a front view of a pin embodying my new design.

The leading feature of my design consists

in the winged head, the head rising from the wings and the wings continuing around the front of the head and meeting as shown.

I claim—

The design for a pin herein shown and described.

JOHN HENRY THEBERATH.
